UNITED STATES PATENT OFFICE.

COSTAS KYRIAKOS, OF FLINT, MICHIGAN.

GAS-SAVER.

1,296,406.

Specification of Letters Patent.

Patented Mar. 4, 1919.

Application filed January 12, 1918. Serial No. 211,663.

To all whom it may concern:

Be it known that I, COSTAS KYRIAKOS, a citizen of the United States, residing at Flint, in the county of Genesee and State 5 of Michigan, have invented new and useful Improvements in Gas-Savers, of which the following is a specification.

This invention has reference to a controlling means for gas burners.

10 The object of the invention is to produce a means designed to obviate the waste of gas occasioned in gas stoves or ranges through failure in turning off the gas supplying a gas burner when the latter is not 15 actually in use. It is a common practice for housewives or cooks to turn on the gas at the commencement or preparation of a meal and to permit the same to burn during the interchanging of utensils upon the stove 20 in the course of cooking various articles for the meal which, of course, results in an unnecessary consumption of gas.

25 The loss of time and the inconvenience and annoyance of intermittently extinguishing and relighting the gas when the cooked articles are removed from the stove for the complete preparation of other articles to be received upon the stove, is so great that such 30 practice is seldom resorted to by the cook, the waste of gas not being considered.

With my improvement, I provide a controller for gas burners which is of such a design and construction, as to be adapted, 35 through the weight of an article or utensil, to be arranged in position for heating over the burner, coöperating therewith and by virtue of such coöperation to permit a free flow of gas to the burner, and upon the removal of the article therefrom, the device 40 automatically operates to shut off or partially shut off the supply of gas to the burner, consequently, extinguishing the flame or permitting the burning of only a small 45 amount of gas, just sufficient to effectively light the burner when a utensil is again arranged over the said burner.

A further object of the invention is to produce a gas control which shall be of a simple nature, readily installed upon any 50 ordinary construction of gas stoves, which shall be positive in action, and which may be cheaply manufactured and installed.

Other objects and advantages will appear as the nature of the invention is better 55 understood, reference being had to the accompanying drawings, in which:

Figure 1 is a detail sectional view of a portion of a gas stove illustrating the application of my improvement thereon.

Fig. 2 is a bottom plan view of the same. 60

Fig. 3 is a sectional view approximately on the line 3—3 of Fig. 2.

Fig. 4 is a sectional view approximately on the line 4—4 of Fig. 2.

Fig. 5 is an elevation, partly in section 65 illustrating the arrangement of parts when the improvement is brought and sustained in inoperative position.

Fig. 6 is a bottom plan view showing the arrangement of parts when a burner is off- 70 set from the gas conducting pipe.

Referring now to the drawings in detail, 75 5 indicates a gas stove or range of any ordinary or preferred construction, 6 the top plate therefor and 7 the hole in the plate.

Centrally arranged beneath hole 7 is a burner 9, the said burner having a pipe connection 10 with the mixing chambers 11, and the mixing chamber is provided with the usual shutter valve 12. 80

The gas manifold is indicated by the numeral 13, and is, as usual, arranged to the outer side of the range 5. Connected with the manifold is the casing 14 for the valve 15 that control the gas between the manifold 85 and the burner. The valve is provided with the usual operating handle 16, and the casing is provided with a pipe extension or nozzle 17 that extends centrally through the shutter 12, into the mixing chamber 11. The 90 pipe extension 17 of the casing of the valve 15 outward of the mixing chamber 11 is provided with a plug valve 18, the outer end thereof being preferably headed as at 19, and the said head being provided with an angular forked extension 20. The mixing chamber 11, upon its under surface, is approximately centrally provided with a depending bracket 21, the same having a rectangular opening 22, and the lower wall provided by 95 the said openings is beveled or inclined from the outer face of the bracket to the inner face thereof, forming the same with what I will term a tooth 23. Designed for free movement through the opening 22 in the bracket 21 is a cross sectionally rectangular rod 24, having, upon its lower edge, a substantially V-shaped notch 26, the purpose of which will 100 presently be described. The outer end of the rod is preferably reduced and round in cross section. This round portion is threaded, as at 24', and is centrally slotted as at 24".

105 21 is a cross sectionally rectangular rod 24, having, upon its lower edge, a substantially V-shaped notch 26, the purpose of which will presently be described. The outer end of the rod is preferably reduced and round in cross section. This round portion is threaded, as at 24', and is centrally slotted as at 24".

The rod 24 is provided with a shoulder 27 and arranged upon the said rod and exerting a tension between the shoulder 27 and the bracket 21 is a helical spring 28 designed 5 to move the rod through the bracket in one direction. The rod, from its shoulder 27, is provided with an angle portion 29, which is pivotally connected as at 30 to the angular end 31 of an arm 32. The arm 32, at its 10 juncture with its angular extension 31 is pivotally connected as at 33 to a lug or bracket 34 formed with or secured to the under face of the pipe 10 or the burner 9, as desired. The arm 32 is provided with an upwardly 15 rounded portion that terminates in a straight extension 35 arranged centrally of the burner 9 and which passes through the opening 7 in the top of the range. The end of the extension 35 has formed thereon a head 36 which 20 is in the nature of a cross or spider, the angular arms providing the said head being inclined downwardly from the center of the head.

The numeral 37' designates a sleeve member 25 designed to receive the outer end of the rod 24 and to have the threaded end 24' partly projecting therethrough. Screwed on the threaded extension 24' of the rod 24 is a nut 25, the same preferably having a round 30 periphery which is milled, and the said nut has, upon its inner extension, a flanged extension 25', which is designed to be engaged by a spring hook 50 that is secured to the sleeve 37. The hook 50 holds the nut in contact 35 engagement with the end of the sleeve 37', and the turning of the nut 25 adjusts the rod 24 with respect to the sleeve. The threaded extension 24' of the rod 24, being centrally slotted, and being constricted 40 of metal, the parts divided by the said slit are adapted to exert an outward tension, or a tension away from each other, and consequently the nut 25, engaging the said slotted threaded portion will compress the bifurcated 45 end thereof to insure the nut against accidental turning. The sleeve 37' is provided, upon its inner end, with an angular finger 37, the outer end of which is bifurcated to receive the forked end 20 of the 50 head 19 of the valve 18. A pin 38 passes through the bifurcated end of the finger and is received between the arms provided by the forked end 20.

The spring 28 normally actuates the members 55 so that the finger 37 will retain the valve 18 closed, but, when the weight of a utensil is placed on the head 36 of the arm member 32, the said arm will be swung upon its pivot 33, sliding the rod 24 outwardly, causing the 60 sleeve 37' to be also moved outwardly and which sleeve, through the medium of the engagement of its finger 37 with the forked extension 20 of the head 19 will turn the valve 18 to permit a flow of gas from the manifold 65 through the valves 15 and 18 to the burner 9.

The removal of the utensil will cause the parts to assume their normal position through the medium of the spring 28, thus closing the valve 18. The valve 18 is so regulated that a small flow of gas is permitted from the manifold to the burner which reduces, but does not extinguish the flame of the burner, so that when a utensil is again placed on the head 36 and the valve 18 operated, as above described, a full flow of gas 70 will be admitted from the manifold through the burner. The gas may remain ignited as long as the valve 15 is turned to its open position. The adjustment of the nut as previously stated, moves the rod 24 longitudinally and, consequently, adjusts the position of the finger 37 of the sleeve 37' with respect to the said rod, and in this manner, the flow of gas through the valve 18 may be 75 regulated.

The valve 18 is preferably of a substantially frusto-conical formation, the reduced end thereof being provided with a headed stud 18' which centrally engages an arched spring member 18'' that has its ends contacting with the valve casing so as to normally and effectively retain the valve on its seat.

To limit and support the arm 32 in its downward movement, I have arranged a 90 yoke 39 upon the under face of the burner 9, and in instances when the employment of my gas control is not immediately required, an outward pull upon the head or handle 25 of the rod 24 against the pressure of the spring 95 28 will cause the V-shaped notch or depression to be engaged by the tooth 23 of the bracket 21, holding the head 36 below the top plate 6 and opening the valve 18 to permit of the free flow of gas from the manifold to 100 the burner upon the turning of the valve 15.

Having thus described my invention, what I claim is:

1. In combination with a gas stove provided with a burner, and a gas controlling valve therefor, having an outlet nozzle communicating with the burner; of a second valve in said nozzle having a head portion provided with an angle forked extension, a spider arranged over the burner, an angle arm connected with the spider and pivotally associated with the burner, a spring pressed rod loosely connected to the angle arm, a guide bracket therefor, said rod having a threaded outer arm which is slotted, a sleeve 110 member on the said outer end of the rod and provided with a finger having a transverse element received in the forked member of the valve head, a nut screwed on the threaded extension of the rod and having its inner 115 face provided with a flanged extension, and a spring hook carried by the sleeve and engaging with the flange of the said extension of the nut, all as and for the purpose specified.

2. In combination with a gas stove provided with a burner and a gas controlling valve therefor having an outlet nozzle communicating with the burner; of a second valve in said nozzle having a head portion provided with an angle forked extension, a spider arranged over the burner, an angle arm connected with the spider and pivotally associated with the burner, a spring pressed rod loosely connected to the angle arm, a guide bracket therefor, said rod being notched to engage in the guide bracket for holding the rod in one position, said rod having a threaded outer extension which is slotted longitudinally, a sleeve slidable on said rod and said threaded extension, a finger on the sleeve co-engaging with the forked extension of the second mentioned valve, and an adjusting element associated with the sleeve and co-engaging with the rod for sliding the sleeve on said rod to regulate the degree of opening of the second mentioned valve.

3. In combination with a gas stove provided with a burner, and a gas controlling valve therefor having an outlet nozzle communicating with the burner, of a second

valve in said nozzle having a head portion provided with an angle forked extension, a spider arranged over the burner, an angle arm connected with the spider and pivotally associated with the burner, a spring pressed rod loosely connected to the angle arm, a guide bracket therefor, said rod being notched to engage in the guide bracket for holding the rod in one position, said rod having a threaded outer extension which is slotted longitudinally, a sleeve slidable on said rod and said threaded extension, a finger on the sleeve co-engaging with the forked extension of the second mentioned valve, a nut on the threaded extension of the valve contacting with the outer end of the sleeve, and means between said sleeve and said nut for holding the nut in engagement with the sleeve.

In testimony whereof I, affix my signature.

COSTAS KYRIAKOS.
